(57) **CLAIM**

The ornamental design for a drawbar for a screen or blind, as shown and described.

DESCRIPTION

FIG. 1 is a front perspective view of a drawbar for a screen or blind according to our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dot-dash broken lines depict the boundary of the claim and form no part of the claimed design. All other broken lines shown in the drawings illustrate environmental structure that forms no part of the claimed design.
